UNITED STATES PATENT OFFICE.

JOHN RODEMEIER, OF FREEPORT, ILLINOIS.

TRUCK FOR MOVING BUILDINGS.

SPECIFICATION forming part of Letters Patent No. 678,035, dated July 9, 1901.

Application filed May 8, 1901. Serial No. 59,264. (No model.)

To all whom it may concern:

Be it known that I, JOHN RODEMEIER, a citizen of the United States, residing at Freeport, in the county of Stephenson and State of Illinois, have invented new and useful Improvements in Building-Moving Trucks, of which the following is a specification.

My invention relates to building-moving trucks; and the object of the same is to construct a truck so designed that several can be coupled together to carry a building during the operation of moving it, the number used depending on the size and weight of the structure and will vary from four up. A novel means for coupling the trucks together is also provided. This object is accomplished by the simple and novel construction described in this specification, and claimed and illustrated in the accompanying drawings, forming a part thereof, in which—

Figure 1 is a side elevation of one of my trucks. Fig. 2 is a vertical longitudinal section of the same. Fig. 3 is a plan view of the same. Fig. 4 is a plan view of four trucks coupled together. Fig. 5 is a section on the line 5 5, Fig. 4.

Like numerals of reference designate like parts in the different views of the drawings.

The numeral 1 designates the frame of my truck, which consists of sides 2 and ends 3, mortised together and secured by tie-rods 4 and drift-bolts 5. Two broad strong-flanged wheels 6 are mounted intermediate the sides 2 and are keyed on the shafts 7, journaled in boxes 8, set into the under side of the frame. The under side of the frame 1 is bound with iron at 2^a, as is also the tops of the ends at 3^a. A platform 9 for supporting the load brought to bear on the truck rests on the upper ends of four pairs of stiff spiral springs 10, each pair of which surrounds a bolt 11 and bears on a base-block 12. The bolts 11 are provided with heads 13, bearing on the upper side of the platform 9, and are fitted with nuts 14, located beneath the base-block 12. The lower ends of the springs 10 rest on the upper face of the base-block 12. A pair of bars 15 extend transversely the frame 1 and are located one on each side of the platform 9. Depending from the bars 15 are four hangers 16, which carry a second pair of bars 17, on which the base-block 12 rests. To keep the

block 12 from slipping off, flanges 18 are provided, which engage the bars 15. By this arrangement the platform 9 has a support which takes up the jar and adjusts itself to the weight and the unevenness of the ground. A brake is fitted on the truck and consists of a bar 19, pivoted intermediate its ends and bearing at its inner end against a brake-block 20, pivoted at its upper end on a cross-pin 21.

In coupling two of my trucks together a bar 22 is pivoted to the platform 9 of each truck. The pairs of trucks so connected are then connected to a pair of stringers 23, which rest in guides 24, mounted on the platform 9 and pivoted to the bars 22. The stringers 23 are also attached by chains 25 to the forward end of each of the trucks. For pulling the four trucks ahead ropes 26 are fastened to the forward ends of the two foremost ones. A drag-arm 27 is pivoted to the rear end of one of the stringers and bears a sharp claw 28, which is adapted to bite into the ground and keep the trucks from running backward when the pull on the rope is slackened. As a track for the trucks in the operation of moving; any strong stringers or old steel rails will do. The stringers may or may not be faced with straps of iron.

In moving a building it is first jacked up and the stringers 23 placed under it, after which the trucks are placed in position and coupled together in the manner described. By means of my trucks buildings of ordinary size may be very expeditiously moved and all danger of breaking their backs avoided.

Only four trucks have been shown coupled together; but it is obvious that any number of pairs could be united in a similar manner.

I do not wish to be limited as to details of construction, as these may be varied in many particulars without departing from the spirit of my invention.

Having thus described my invention, what I claim as new, and wish to secure by Letters Patent, is—

1. A moving-truck comprising the combination, of a frame, broad wheels flanged on both sides mounted intermediate the sides of said frame or shafts journaled therein, bars extending across said frame, hangers depending from said bars, a base-block supported on said hangers, springs mounted on

said base and a platform resting on said springs, substantially as described.

2. In a moving-truck, the combination with a rectangular frame mounted on wheels, of 5 bars extending transversely said frame, hangers depending from said bars, a base supported by said hangers, a platform, bolts connecting said base and said platform and springs mounted on said bolts and bearing 10 on said platform and said base, substantially as described.

3. The combination with four trucks, provided with platforms, of two bars pivoted to

15 said platforms and uniting them transversely in pairs, guides pivoted to said bars, and 15 stringers fitting said guides and connected to said trucks by chains, substantially as described.

20 In testimony whereof I have hereunto set my hand in presence of two subscribing witnesses.

JOHN RODEMEIER.
